UNITED STATES PATENT OFFICE.

RAY D. ROBINSON, OF LOS ANGELES, CALIFORNIA.

ORTHODONTIC APPLIANCE.

1,114,291.

Specification of Letters Patent. Patented Oct. 20, 1914.

Application filed April 9, 1914. Serial No. 830,752.

To all whom it may concern:

Be it known that I, RAY D. ROBINSON, a citizen of the United States, residing at Los Angeles, in the county of Los Angeles and State of California, have invented a new and useful Orthodontic Appliance, of which the following is a specification.

This invention relates to an appliance to be used in correcting the positions of malposed teeth, in which a pressure may be exerted upon the tooth in any direction to change the tooth from an abnormal position to a normal position, and the object of the invention is to provide such a construction which may be expeditiously employed to effectively accomplish this.

Referring to the drawings: Figure 1 is a front elevation of the teeth of the upper jaw with the appliance secured thereto. Fig. 2 is a side view of what is shown in Fig. 1. Fig. 3 is an occlusal view of what is shown in Fig. 1. Fig. 4 is an enlarged front elevation of the non-revolute engaging means. Fig. 5 is a front elevation of the tooth band showing the engaging means in longitudinal section on line x^6-x^5 , Fig. 6. Fig. 6 is a section on line x^6-x^5 , Fig. 4. Fig. 7 is a perspective view of the wire and block. Fig. 8 is a perspective view in detail of the tooth band and sleeve.

The essential feature of the invention comprises a non-revolute means for connecting the arch band 1 with a tooth band 2, said non-revolute means permitting a longitudinal adjustment between the arch band and tooth band. This connecting means in the present embodiment comprises a block 3, which is soldered or otherwise secured on the arch band 1, and the block 3 is received in a sleeve 4 which is soldered or otherwise secured to the tooth band 2. The precise form of the block 3 and sleeve 4 is immaterial, but it is essential that these two members be so constructed with interengaging faces that revolute movement between them is prevented, while longitudinal adjustment is possible. In the present instance, the block 3 is shown as having four flat sides, and the sleeve 4 is shown as tubular in cross section. In order to retain the block 3, the outer flanges of the sleeve shown in Fig. 8 are bent down as at 5 over the outer face of the block 3 as shown in Fig. 6, and the sleeve is thus capable of withstanding a torsional reacting strain on the arch band 1 from the tooth band 2 and tooth. Thus,

when a tooth stands at a correct angle erect but is out of normal position and must be moved to correct position without altering its erect angle, the arch band is moved in 60 the requisite direction which exerts a corresponding pressure on the tooth band and tooth. The important feature of the construction is that the non-revolute connection between the arch band and tooth keeps 65 the tooth at the same angular position in all directions, with respect to the arch band so that although the connection is with the crown and there is greater resistance by the root, this resistance does not disturb the 70 angular relation but is gradually overcome so that in time the entire tooth has been moved bodily to correct position without its erect angle having been altered.

If the angular direction of the short axis 75 of the tooth is to be altered a strain on the arch band will be imparted to the tooth as indicated. Thus, in Fig. 1, the left lateral incisor 6 will have a torsional strain in a horizontal plane imparted to it which will 80 correct it. A torsional strain in a vertical plane may be imparted to the tooth to alter its longitudinal inclination. As this pressure is a spring pressure, it is constantly exerted and continues until the movement of 85 the tooth toward a normal position has taken up all of the spring tension, at which time the arch band should again be adjusted to exert pressure on the tooth for a further period of time, and this operation is continued until the tooth has acquired a normal position. The rotative pressure against the tooth is secured in the following manner: The arch band is first set in position, being secured to the anchor teeth, and the intermediate tooth band is placed in position over the tooth which is to be corrected, and this tooth band is secured temporarily rigidly to the arch band through the medium of its sleeve and block 3. The flanges 5 of 100 the tooth bands are then bent out to allow the block 3 to move out laterally and then the arch band is removed and the block 3 of the intermediate tooth band is unsoldered from the arch band, and revolved slightly 105 on the arch band in the required direction, and then again soldered rigidly in position. The arch band is then placed in the mouth and its ends are connected with the tooth bands of the anchor teeth as before, but to 110 connect the intermediate tooth band with the tooth which is to be corrected, it is now

necessary by reason of the altered angle of this tooth band to spring it, placing a torsional strain on the arch band, in order to slip it onto the tooth which is to be corrected, and this is done so that when this intermediate tooth band immediately exerts a rotative pressure on the tooth, and this rotative pressure constantly acts upon the tooth, and the tooth gradually responds thereto until the tooth has moved toward the desired angle and the rotative pressure has gradually become lessened until its effect is gone. Then the arch band is removed from the mouth, and the block 3 of the intermediate tooth band is again unsoldered and again slightly turned and then resoldered and the arch band placed back in position again, and the intermediate tooth band again sprung over the tooth to be corrected and the process is repeated until the tooth has moved into the desired position. This removal and replacement of the arch band is easily accomplished by bending the flanges 5 of the tooth bands. The tooth bands themselves are not removed. It is obvious that the arch band may be also so bent as to produce any component of pressure between the two planes noted to correct a corresponding irregularity. The tooth is apt to stand at an angle to its normal position both vertically and horizontally, and in such case the arch band would be given a bend which would tend to exert a pressure on the tooth in a direction which would correct both of these angular displacements. In this manner, the pressure is exerted independently on each tooth, and it is thus possible to apply the exact pressures and in the exact directions which are needed for each individual tooth, so that several teeth, while being corrected at the same time, are each individually under definite strains required to bring them to their respective normal positions.

In setting the appliance, the blocks 3 may be slid longitudinally in the sleeves 4 when desired, after which, to present further longitudinal movement, the sleeve may be indented with pliers to hold the block from sliding endwise. The ends of the arch band are connected to terminal sleeve 9 secured to anchor teeth 10.

What I claim is:

1. In an orthodontic appliance, an arch band, an open angular sleeve between the anchored ends of the arch band, means for securing the sleeve to a tooth which is to be moved, means supporting the ends of the

arch band, and a non revoluble block adjustable slidably in said sleeve and rigidly secured at an intermediate point to the arch band.

2. In an orthodontic appliance, block engaging means adapted to be secured to a tooth, an angular block removably secured in said block engaging means, an arch band, means supporting the ends of the arch band, said block being non-rotatably secured to an intermediate portion of the arch band whereby a rotative pressure of the arch band is transmitted through said block and said block engaging means to the tooth.

3. In an orthodontic appliance, an arch band, means supporting the ends of the arch band, an angular block secured to an intermediate portion of the arch band, an angular sleeve having an open front, and means securing said sleeve to a tooth, said sleeve having a recess with a flat surface and receiving said block.

4. In an orthodontic appliance between the anchored ends of the arch band, an angular sleeve having an open front side, means securing said sleeve to a tooth, a block rigidly fitted in said sleeve, said sleeve being provided with means engaging the outer face of the block to detachably retain the block in said sleeve, and means for holding said block in the desired angular position to cause the block to exert pressure through said sleeve and sleeve securing means to the tooth.

5. In an orthodontic appliance, a sleeve, means securing the sleeve to a tooth, a block adjustable slidably in said sleeve and secured to the arch band, the walls of said sleeve being bent over the sides of the block.

6. An orthodontic appliance comprising a band adapted to encircle a tooth, a sleeve on said band rectangular in cross section, a block rectangular in cross section interlocking in said sleeve, said block having a circular bore, an arch band comprising a wire circular in cross section extending through the bore of the block, means holding the block against revoluble movement with respect to said wire, and means supporting the ends of said wire.

In testimony whereof, I have hereunto set my hand at Los Angeles, California, this 3d day of April, 1914.

RAY D. ROBINSON.
